WRITING INSTRUMENT

Julian Gutierrez Marban, Miramar, Havana, Cuba
(6233 Brookview Ave. S., Minneapolis 24, Minn.)
Filed May 2, 1960, Ser. No. 26,147
5 Chims. (Cl. 120—42.16)

This invention relates to writing instruments and has special reference to a fountain pen of the double reservoir type, having valves which normally seal at least one of the reservoir sections from access to the atmosphere.

More particularly, this invention pertains to a fountain pen including a barrel having a first valve dividing the interior thereof into auxiliary and primary reservoir sections, a writing element mounted on the forward end of the barrel, and a second valve within the barrel between the auxiliary reservoir section and the writing element, there being an axially movable filling member mounted within the barrel and extending from the rearward end of the primary reservoir to a position beyond the forward end of the barrel, the filling member being operatively connected to the valves and movable from an intermediate position closing both valves to a rearward position opening only the second valve and to a forward position opening only the first valve, the pen including means for selectively sealing the rearward end of the filling member.

In the usual type of fountain pen, it is necessary to allow for the controlled entry of air into the reservoir to replace the fluid used during writing. Because of the difference in weight, the air rises above the writing fluid in the reservoir and remains thereabove regardless of the position in which the fountain pen subsequently may be held.

The air thus present in a fountain pen reservoir is affected by the same influences as free atmospheric air, and it will expand or contract if subjected to fluctuations in temperature and/or pressure. Ordinarily an environmental change which causes contraction of air will not adversely affect a pen, and in certain instances it may prove beneficial by drawing into the reservoir any excess fluid which might be in the expansion chambers or fluid channels of the feed bar.

On the other hand, a decrease in barometric pressure or an increase in temperature may readily cause an undesirable condition in the usual fountain pen should it be held in a position resulting in isolation of air in the closed end of the reservoir. Under these conditions a quantity of fluid, equal to the increase in air volume, will be forced from the reservoir and into the expansion chambers of the feed. If the expansion chambers are not of sufficient capacity, a portion of this fluid will drip from the instrument into the cap or blot the writing surface or soil the user's hands or clothing. It has been observed that this is a particularly vexing problem in air travel in which extremes of temperature and pressure changes are encountered in relatively short periods of time. Of course, if the pen is positioned point upwardly when the above described expansion occurs, the excess air in the reservoir will readily escape through the feeding passageways without causing difficulty.

It has been observed that a large percentage of users are not aware of or do not understand the above outlined phenomenon of air expansion in the fluid reservoir, and should a pen be found flooded they assume that it is defective and return it to the manufacturer for adjustment or replacement. This causes a great deal of needless inconvenience to the users and expense for the manufacturers since the pens are completely up to standards in a large majority of cases.

Furthermore, in filling the usual pen, it is necessary to completely immerse the point and feed in a body of

2

fluid to insure that the reservoir is properly filled. Thus, after completing the filling operation a substantial amount of fluid usually adheres to the point and feed and it is necessary to remove this residual fluid with a cloth or tissue to prevent it from blotting the writing surface or soiling the user's hands during subsequent use of the instrument. Also, the excess fluid in the expansion chambers should be removed to permit proper functioning thereof immediately after filling.

These problems have long been recognized in the art, and numerous suggestions and proposals have been made for their solutions. For example, it has been proposed in the past to provide a substantially air tight point protector or cap to prevent the expansion of air in the reservoir even though it should be subjected to an increase in temperature or a decrease in pressure. However, if the unvented cap is removed under such conditions and if at that time the pen is held flat or in a point-down position, a quantity of fluid may suddenly be expelled from the writing element.

My United States Patent No. 3,023,737, dated March 6, 1962, discloses a fountain pen having a divided reservoir and a common member for filling said reservoir and controlling communication between the reservoir sections and the writing element. The present invention discloses a fountain pen of the same generic class, but having improved valve means, an improved filling member and a minimum number of parts with the attendant manufacturing and maintenance economies.

Accordingly, it is a principal object of this invention to provide a fountain pen which is not subject to the loss of fluid as a result of temperature or barometric pressure changes.

Another object of this invention is to provide a fountain pen having a large but controlled fluid capacity.

A further object of this invention is the provision of a fountain pen which may be readily filled with a large quantity of writing fluid but which is always in condition for immediate and clean writing even though subjected to extreme and rapid changes in ambient temperature and pressure.

An additional object of this invention is to provide a fountain pen having a primary fluid reservoir which is normally isolated from the atmosphere except during the filling operation.

A still further object of this invention is the provision of a fountain pen having a normally sealed primary reservoir and a normally vented auxiliary reservoir from which fluid is withdrawn during writing but which may be readily replenished from the primary reservoir by simple manipulation.

Yet another object of this invention is to provide a fountain pen which has the characteristics mentioned above and which eliminates the necessity of immersing the writing element in fluid during the filling operation.

An additional object of this invention is the provision of a fountain pen having a large fluid reservoir divided into two sections, and manually operable valve means to control communication between said sections and the writing element.

A still further object of this invention is to provide a fountain pen having a divided reservoir and a common member for filling the reservoir sections as well as controlling communication between the reservoir sections and the writing element.

Yet another object of this invention is the provision of a fountain pen having a divided reservoir and a filling member extensible beyond the forward end of the writing element for immersion in a body of writing fluid during the filling operation.

Further and additional objects of this invention will be

apparent from the following description when taken with the accompanying drawings in which:

FIGURE 1 is a longitudinal sectional view of a fountain pen embodying this invention and illustrating the arrangement of parts as conditioned for writing or storage;

FIGURE 2 is a fragmentary sectional view of the forward portion of the embodiment of FIGURE 1, showing a change in position of the parts as conditioned for filling and transferring fluid between the reservoir sections;

FIGURE 3 is a fragmentary sectional view of the forward portion of the embodiment of FIGURE 1, showing another change in position of the parts; and

FIGURE 4 is an enlarged sectional view taken along the line 4—4 of FIGURE 1.

Referring first to FIGURES 1 through 3 of the drawings, the fountain pen therein illustrated includes a barrel 10 formed of a substantially unbreakable rigid plastic or metal having dimensional stability and a lustrous and long wearing surface. The barrel 10 consists of lower and upper portions 11 and 12, respectively, and a substantially conically shaped barrel cap 13, all of which are threadedly or otherwise removably secured together in axial abutting alignment.

Mounted on the barrel 10 is a forwardly projecting writing element 14, which comprises a substantially non-corrodible metallic pen point 15 of the usual configuration, and a feed bar 16 fabricated from a hard rubber or like material and juxtaposed against the underside of the point. For convenience in assembly and subsequent maintenance, the point 15 and feed bar 16 preferably are pressed into an annular collar or point holder 17 which, in turn, may be threadedly secured within the open forward end of the lower barrel portion 11. For reasons well understood in the art, the feed bar 16 is provided with a capillary fissure 18 which is adopted for fluid communication with the writing tip 19 through the slit 20.

Communication between the interior of the barrel 10 and the fissure 18 is provided through a passageway 21 extending through the central portion of the feed bar 16 and including a rearward bore 22 of increased diameter.

In order to accomplish the objectives of this invention, it is necessary to divide the interior of the barrel into separate fluid sections. For this purpose, a first valve is provided within the barrel of the pen dividing the interior thereof into the necessary reservoir sections, an auxiliary reservoir section 23 and a primary reservoir section 24. While it is apparent that the valve may be formed in various ways, it is shown in the drawing as including an annular resilient sealing member or gasket 25, and a first wall portion 26 providing a passage 27 adapted to sealably and slidably engage the resilient sealing gasket 25. The first wall portion 26 preferably is formed as an integral part of the barrel 10, and includes a rearwardly extending cup like portion 28 having a plurality of transverse radially positioned apertures 29 spaced a short distance forwardly of the shoulder 30. The apertures 29 are adapted to provide communication between the primary reservoir 24 and the passage 27 when the gasket 25 is moved to the "flushing" position to be described in more detail hereinafter.

The gasket 25 is mounted in an annular recess adjacent the enlarged rearward end of an elongated cylindrical member 31 which is axially movable within the passage 27 and auxiliary reservoir 23. As indicated by the drawing, the gasket 25 tightly engages the annular recess in the cylindrical member 31 so as to insure against the movement of fluid therebetween.

It is understood, of course, that the materials used in the sealing assembly, comprising the gasket 25 and the cylindrical member 31, and various other parts subject to contact with writing fluid, are selected from materials well-known to those in the art as being non-reactive with the constituents of the usual writing fluid. Further, as used in this specification the term "valve" is under-

stood to include the entire structure adapted to close one fluid section from another and not merely a movable part thereof. For instance, as described in the preceding paragraph, the term "valve" includes both the wall portion 26 and the axially movable gasket 25.

The primary reservoir section 24 preferably is several times larger in volume than the auxiliary reservoir section 23, serving as a sealed fluid storage area of a size limited only by the desired external dimensions of the barrel 10. In contrast, the size of the auxiliary section 23 is relatively limited and its volume is calculated to insure it is "functionally balanced" with the capacity of a series of transverse annular expansion chambers 32 in the feed bar 16. In other words, the expansion chambers 32 should be equal to or greater in volume than the maximum amount of fluid which can be forced from the auxiliary reservoir under the most adverse temperature and/or pressure conditions that the pen is likely to encounter in normal use.

A second valve is positioned within the barrel 10 forwardly of the first valve and between the auxiliary reservoir section 23 and the writing element 14. This valve includes a second wall portion 33 and the reduced forward portion 34 of the cylindrical member 31. The wall portion 33 is molded or otherwise formed of a resilient rubber or plastic material, and it includes an outlet 35 sized to sealably and slidably engage the reduced forward portion 34. While various other arrangements may be used, the wall portion 33 is provided with an enlarged annular base 36 which is retained tightly within a recess formed between the rearward end of the feed bar 16 and the forward surface of a collar 37, the collar 37 being threadedly or otherwise mounted on the upper end of the point holder 17.

One of the important features of this invention is the provision of a single common member for filling the pen and for actuating the valves to control fluid communication between the reservoir sections and the writing element. This feature is accomplished by the use of an elongated filling member 38 which is coaxially mounted for longitudinal movement within the barrel 10 and passageway 21 of the feed bar 16, and which defines a fluid path extending from a fluid discharge 39 adjacent the rearward end of the primary reservoir to a fluid intake 40 positioned adjacent the forward end of the feed bar 16. The sealing assembly is frictionally or otherwise mounted on the filling member 38 and is axially movable therewith as a unit.

Mounted substantially intermediate to ends of the filling member 38 is a transversely extending spline member 41, the outer ends of which are slidably received in longitudinally extending grooves 42 formed in the threaded connector 43. This is best shown in FIGURE 4. Engagement between the spline member 41 and grooves 42 effectively prevents rotation of the filling member 38 relative to the barrel 10.

While various filling arrangements may be employed in this invention, the illustrated embodiment includes a resilient plastic or rubber sack 44 having an open forward end securely mounted on a flange 45 extending rearwardly of the threaded connector 43.

The rearward end 46 of the sack 44 preferably is of a reduced diameter so as to telescopically receive a formed plastic or metallic cover 47. In order to insure retention of the formed cover 47, a coupling 48 is mounted on the filling member 38 a short distance from the rearward end thereof. The cylindrical wall of the coupling includes an annular indentation adapted to receive an inwardly extending annular projection 49 formed adjacent the forward end of the cover 47, with the sack being squeezed between the coupling 48 and the cover 47 as indicated in FIGURE 1.

During normal use and storage of the pen, the fluid discharge 39 should be closed in order to prevent the ingress of air into the primary reservoir section. For this purpose, means comprising a rotatable button mem-

ber 50 is threadedly engaged in the rearward wall of the cover 47. The forward surface of the rotatable member 50 should have a smooth and polished surface to insure against damage to the rearward closed end of the sack 44. Further, the rearward end of the filling member 38 may be turned outwardly or flared by a burnishing or similar operation so that the sack 44 will not be cut or otherwise damaged when pressed thereagainst by the rotatable button member 50 as it is manually moved to the position illustrated in FIGURE 1 to close the fluid discharge 39. As further insurance against damage to the sack 44, the rotatable member 50 may be provided with an enlarged shoulder 51 as a means of limiting its forward movement relative to the cover 47.

As is readily apparent from the above description and the drawing, the sack 44 forms an integral part of the primary reservoir 24.

During normal writing use as well as storage of the pen, the filling member 38 and sealing assembly (gasket 25 and cylindrical member 31) are disposed in the rearward position illustrated in FIGURE 1 of the drawing. In this position, the gasket 25 is sealably engaged within the passage 27 to isolate the primary reservoir section from the auxiliary reservoir, and the reduced forward portion 34 of the elongated cylindrical member 31 is spaced from the resilient second wall portion 33. Thus, the outlet 35 between the auxiliary reservoir section 23 and the writing element 14 is open. Accordingly, even under the most severe temperature and/or pressure conditions, the first valve will positively prevent the escape of any air or fluid from the primary reservoir. And because the expansion chambers 32 of the feed bar 16 will retain the maximum amount of fluid which might be forced from the auxiliary reservoir section, the heretofore relatively common difficulty of leakage is eliminated.

During writing use, as will be obvious to those skilled in the art, fluid will be drawn from the auxiliary reservoir 23, through outlet 35 and passageway 21 to the capillary fissure 18 in the feed bar 16. It will then transfer from the capillary fissure 18 to slit 20 and to the writing tip 19.

The primary feature of the present invention is to prevent direct communication between the primary reservoir 24 and the writing element 14, and to accomplish this feature it is necessary to arrange the parts of the valves so that movement of the filling member toward the forward position shown in the FIGURE 2 subsequently causes the second valve to close and the first valve to open. Thus, during normal use of the pen only one valve is open at any one time and this continuous isolation of the primary reservoir 24 effectively prevents expulsion of fluid therefrom into the writing element regardless of temperature or pressure conditions.

To subsequently close the second valve and open the first valve to establish communication between the reservoir sections, while they are isolated from the writing point, it is merely necessary for the user to remove the barrel cap 13 and press forwardly on the rotatable button member 50 until the forward end of the elongated cylindrical member 31 abuts the shoulder formed by the enlarged rearward bore 22 of the feed bar 16. The valves then assume the position illustrated in FIGURE 2 in which the gasket 25 is spaced from the first wall portion 26, and the forward sealing element, formed by the reduced forward portion 34 of the cylindrical member 31, is sealably engaged with the second wall portion 33. The passage 27 is substantially longer than the thickness of the gasket 25 and a fluid and air tight seal is maintained therebetween as long as any portion of the gasket is within the passage. Since the gasket normally is spaced from the forward end of the passage 27 when the filling member 38 is in the rearward position, the first valve remains closed during a substantial portion of the forward movement of the filling member and the sealing assembly toward the forward position and until after the second valve is closed. Thus, when the filling member

is intermediate the forward and rearward positions, both valves are closed and the reservoir sections are isolated from each other and from the writing element as clearly indicated in FIGURE 3.

As stated previously, if the user wishes to transfer fluid between the reservoir sections, it is merely necessary to remove the barrel cap 13 in order to move the filling member 38 and its associated parts to the forward position. During this operation, the upper part of the barrel 12 should remain assembled with the balance of the pen so as to prevent any "bulging" of the sack 44. Due to the resiliency of the sack 44 and its compression within the confines of the upper barrel portion 12, it will readily return the filling member 38 and its associated parts to the rearward position upon removal of the forward pressure on rotatable member 50.

Should the user wish to fill the reservoir sections, however, the upper barrel portion 12 and barrel cap 13 should be removed as a unit from the balance of the instrument. Thus, upon forward movement of the filling member 38 to the forward position, the sack 44 will "bulge" outwardly to some extent. Thereafter, the fluid discharge 39 should be opened by rotating the member 50, which rotation allows the closed rearward end 46 of the sack 44 to move rearwardly from the fluid discharge 39 because of its inherent resiliency. The exposed forward end of the filling member 38 may then be dipped in a body of writing fluid, and the sack subjected to a squeezing pressure in order to evacuate the reservoir and draw fluid thereinto through the fluid intake 40, the filling member 38 and the fluid discharge 39.

To permit free movement of air and fluid during the filling operation, the coupling 48 is provided with apertures 52 adjacent the forward end thereof, the apertures communicating with the space between the outside surface of the filling member and the inside wall of the coupling. And since the first valve is open during the filling operation both reservoir sections may be filled with fluid in order to insure a full charge.

In order to keep the wall of the sack 44 as thin as possible, the interior thereof is provided with a plurality of transverse reinforcing ribs 53 to assist the sack in returning to its distended condition after being deflated during the filling operation.

After the reservoir sections have been completely charged with fluid, the filling member 38 and its associated parts should be moved to the rearward position in FIGURE 1, and this may be accomplished merely by grasping the rotatable member 50 and moving it rearwardly relative to the lower barrel portion 11. The pen may then be conditioned for writing or storage by rotating the member 50 to close the fluid discharge 39, whereafter the upper barrel portion 12 and barrel cap 13 may then be reassembled with the lower barrel portion 11.

In order to empty the filling member 38 of any residual fluid following the filling operation, the fluid discharge 39 should remain open as the filling member 38 is moved from the forward to the rearward position. During this movement, the interior volume of the sack 44 will increase slightly, thus drawing any residual fluid from the interior of the filling member into the primary reservoir section.

The upper end of the passageway 27 may be of a slightly reduced diameter in order to provide a shoulder 54, best seen in FIGURE 2, against which the gasket 25 abuts when the filling member 38 and parts carried thereon are in the rearward or "writing" position illustrated in FIG. 1.

In addition to the three positions described previously, the filling member 38 and valves may assume what would be termed the flushing position. In this position, the first and second valves are open simultaneously so that both reservoir sections are in communication with the atmosphere through passageway 21 in feed bar 16 and the other associated capillary channels described previously. To reach this position, the filling member 38 and parts carried

thereon are manually moved rearwardly (after removal of the upper barrel portion 12 and the barrel cap 13) thus urging the gasket 25 within the reduced rearward end of the passageway 21 and causing it to move upwardly therein until it abuts the inwardly extending shoulder 30 disposed at the upper end of passage 27. Thus, the gasket 25 is above the apertures 29, and fluid can be expelled from both reservoir sections through the writing element upon deflation of the sack 44 with the fluid discharge 39 closed.

During normal writing use the auxiliary reservoir 23 may be replenished from time to time by moving the valves to the forward position while the pen is positioned with the point downwardly toward the writing surface. This forward movement of the valves and associated filling member 38 will result in a slight deflation of the rearward end of the sack 44, and in combination with the force of gravity the pressure in the sack 44 will cause fluid to flow from the primary reservoir 24 through passage 27 and into the auxiliary reservoir 23, while air from the auxiliary reservoir simultaneously enters the primary reservoir from the auxiliary reservoir during the transfer of fluid therebetween.

It is understood, of course, that the pen of the present invention is adapted to receive a cap or point protector of the usual type in order to prevent evaporation of the writing fluid from the point and feed bar during periods when the instrument is not in use.

While only one embodiment is illustrated and described herein it is understood that this invention is not to be limited thereto as many modifications may be made without departing from the true spirit and scope of this invention. Accordingly, the invention is not to be limited to the embodiment described above and it is contemplated, by the appended claims, to cover any such modifications which fall within its true spirit and scope.

I claim:

1. A writing instrument comprising a barrel, a first valve within said barrel dividing the interior thereof into auxiliary and primary reservoir sections, a flexible wall member closing the rearward end of said barrel, a writing element mounted on the forward end of said barrel and including a pen point and a feed bar having a central aperture therethrough, a second valve within said barrel between said auxiliary reservoir section and said writing element, an axially movable filling member mounted within said barrel said filling member defining internally thereof a continuous fluid path extending from a fluid discharge adjacent the rearward end of said primary reservoir through said central aperture to an exposed fluid intake adjacent the forward end of said feed bar, said filling member being operatively connected to said valves and movable from an intermediate position closing both said valves to a rearward position opening only said second valve and to a forward position opening only said first valve, and manually operable means for moving said filling member between said recited positions, said means including a button member reciprocal relative to said filling member for urging said flexible wall member into sealing engagement with said fluid discharge to isolate said fluid path from said primary reservoir, said flexible wall member being compressible whereby fluid may be drawn into said reservoir sections upon rendering said sealing means ineffective and immersing said exposed fluid intake in a body of fluid.

2. A writing instrument comprising a barrel, a first wall portion within said barrel dividing the interior thereof into auxiliary and primary reservoir sections and providing a passage between said reservoir sections, a writing element mounted on the forward end of said barrel, a second wall portion within said barrel and defining an outlet between said auxiliary reservoir section and said writing element, an axially movable filling member mounted within said barrel, said filling member defining internally thereof a continuous fluid path extending through said passage and said outlet

wall portions from a fluid discharge adjacent the rearward end of said primary reservoir to an exposed fluid intake disposed beyond the forward end of said barrel adjacent said writing element, a sealing assembly carried on said filling member, and movable therewith from an intermediate position closing both said passage and said outlet, to a rearward position opening only said outlet, and to a forward position opening only said passage, and manually operable means for moving said filling member between said recited positions, said means further being operable for selectively sealing said fluid discharge to isolate said fluid path from said primary reservoir.

3. A writing instrument comprising a barrel, a first wall portion within said barrel dividing the interior thereof into auxiliary and primary reservoir sections and providing a passage between said sections, a flexible wall member closing the rearward end of said primary reservoir, a writing element mounted on the forward end of said barrel, a second wall portion within said barrel and defining an outlet between said auxiliary reservoir section and said writing element, an axially movable filling member mounted within said barrel, said filling member defining internally thereof a continuous fluid path extending through said passage and said outlet from a fluid discharge adjacent said flexible wall member to an exposed fluid intake positioned beyond the forward end of said barrel adjacent said writing element, a sealing assembly carried on said filling member and including forward and rearward sealing elements, said filling member and said sealing assembly being movable as a unit to an intermediate position in which said forward sealing element closes said outlet and said rearward sealing element closes said passage, to a rearward position in which said forward sealing element is spaced from said second wall portion and said rearward sealing element is disposed within said passage, and to a forward position in which said forward sealing element is positioned within said outlet and said rearward sealing element is spaced from said first wall portion, and a button member disposed rearwardly of said flexible wall member, said button being reciprocal relative to said barrel for moving said filling member between said recited positions, said button member further being reciprocal relative to said filling member for selectively urging said flexible wall portion into sealing engagement with said fluid discharge to isolate said primary reservoir from said fluid path.

4. A writing instrument comprising an elongated barrel, a first wall portion within said barrel dividing the interior thereof into a small auxiliary reservoir section and a larger primary reservoir section, said first wall including a centrally disposed passage for fluid communication between said reservoir sections, a flexible sac closing the rearward end of said primary reservoir, a writing element mounted on the forward end of said barrel and including a pen point and a feed bar having a central aperture therethrough, a second wall portion within said barrel forwardly of said first wall portion, said second wall portion defining a centrally disposed outlet providing communication between said auxiliary reservoir section and said writing element, an axially movable elongated filling member mounted within said central aperture and said barrel, said filling member defining internally thereof a continuous fluid path extending through said passage and said outlet from a fluid discharge adjacent said flexible sac to an exposed fluid intake adjacent the forward end of said feed bar, a sealing assembly carried on said filling member and including forward and rearward sealing elements, said filling member and said sealing assembly being movable as a unit to an intermediate position in which said forward sealing element closes said outlet and said rearward sealing element closes said passage, to a rearward position in which said forward sealing element is spaced from said second wall portion and said rearward sealing element is sealed within said passage, and to a forward position in which said forward sealing element is sealed within said outlet and

9
said rearward sealing element is spaced from said first wall portion, and a manually operable button being longitudinally reciprocal relative to said barrel to move said filling member between said recited positions, said button member further being longitudinally movable relative to said filling member for selectively urging said sac into sealing engagement with said fluid discharge thereby isolating said primary reservoir from said fluid path.

5. A writing instrument comprising an elongated barrel, a first transverse wall portion within said barrel dividing the interior thereof into a small auxiliary reservoir section and a larger primary reservoir section having a resilient rearward area, said first wall portion including a centrally disposed passage for fluid communication between said reservoir sections, a writing element mounted on the forward end of said barrel and including a pen point and a feed bar having a longitudinally extending central bore therethrough, a second transverse wall portion within said barrel forwardly of said first wall portion, said second wall portion having an outlet providing communication between said auxiliary reservoir section and said feed bar, a filling member mounted for axial movement within said central bore and said reservoir sections, said filling member providing a fluid path extending from a fluid discharge adjacent the rearward end of said primary reservoir to a fluid intake positioned adjacent the forward end of said feed bar, a sealing assembly carried on said filling member and including forward and rearward seal-

5
ing elements, said filling member and said sealing assembly being movable as a unit to an intermediate position in which said forward sealing element sealably engages said outlet and said rearward sealing element sealably engages said passage, to a rearward position in which said forward sealing element is spaced from said second wall portion and said rearward sealing element sealably engages said passage, and to a forward position in which said forward sealing element sealably engages said outlet and said rearward sealing element is spaced from said first wall portion, said fluid intake being extended beyond said pen point when said filling member is in said forward position, and manually operable closure means for selectively urging said resilient area against the rearward end of said filling member for sealing said fluid discharge, said resilient area being compressible whereby fluid may be drawn into said reservoir sections upon rendering said sealing means ineffective and immersing said fluid intake in a body of fluid.
